UNITED STATES PATENT OFFICE

WILLIS W. HARGROVES, JR., OF PORTSMOUTH, VIRGINIA, ASSIGNOR TO PLANTERS MANUFACTURING CO., INC., OF PORTSMOUTH, VIRGINIA, A CORPORATION OF VIRGINIA

SHIPPING BASKET COVER FASTENER

Application filed July 2, 1931. Serial No. 548,425.

The present invention relates to a fastener for securing the tops and covers of shipping containers or the like, and has particular reference to fasteners for the covers of vegetable or fruit baskets.

It is the object of the present invention to provide for the above stated purposes a fastener of a unitary construction and carried solely by the basket body and having 10 interengageable locking parts, one of which will extend through an opening in the cover and is movable to interengaging position with the other part, whereby the cover may be firmly fastened and held in place, said invention 15 being quickly disengageable, without the aid of tools, to permit the removal of the cover.

It is also an object of the invention to provide a fastener for shipping basket covers 20 and which comprises interengageable parts carried by the container or basket, one arranged on the inside of the basket wall and the other on the outside thereof, in substantially parallel relation with its side-wall 25 whereby the baskets may be readily nested and stacked without injury or deformation to said fastener, or in anywise hindering the packing or removal of the contents of the basket.

A still further object of the invention is the provision of a fastener for the covers of shipping baskets, wherein the fastener is provided with two upwardly projecting interengageable parts carried by the body of the basket and disposed on opposite faces of a side wall thereof and at its upper edge, said parts of the fastener extending beyond the upper edge of the basket, whereby the edge portion of the cover will be received between 30 said interengageable portions of the fastener to prevent radial shifting movement of the cover in either direction, one of said interengageable portions of the fastener extending through the cover and both being of such length as they may be bent one over the other.

With the above and other objects in view, the invention resides in the sundry details of construction, combination and arrangements of parts hereinafter more fully de-

scribed and pointed out in the appended claim.

In the drawing, which shows by way of example an embodiment of the invention as at present devised:

Figure 1 shows a perspective view of the basket equipped with the fasteners of the present invention and securing the cover thereof in position;

Figure 2 is a fragmentary sectional view 55 through the cover edge portion of the basket and showing the normal position of the fastener before it is moved to fastening position and, also, illustrating the position the outer edge of the cover assumes with respect 60 to the parts of the fastener;

Figure 3 is a view similar to Figure 2 and showing parts of the fastener in interlocking position;

Figure 4 is a fragmentary elevation of the 70 structure shown in Figure 3. Figs. 5 and 6 illustrate modifications, and

Fig. 7 is a view of the loop from which the fastener is formed.

The container or basket on which the present invention is adapted for employment may be of any of the common types now generally in use for packing and shipping fruits, vegetables and the like. The basket B is formed, usually, by a plurality of wooden 75 staves or splints 10, upwardly extending to form the side wall of the basket, and held in position and reinforced at their upper edge between inner and outer hoops 11 and 12 and, if desired, by intermediate hoop or hoops 80 13. The bottom 14 of the basket may be of any suitable construction.

The top or cover T may be of the usual type and may comprise a hoop or rim 15, which is of the same size as the basket rim, 90 and a series of slats 16 arranged in any desired manner and nailed or otherwise fastened to the rim hoop 15. It is ordinarily desirable to have the staves 10 of the basket and the slats 16 of the cover spaced apart for 95 ventilation purposes; however, this is not necessary, but with respect to the top it is desired to have suitable openings 16a provided adjacent its rim 15 through which the fastener member may extend and such open- 100

ings may be provided by the spaces between the slats 16.

To or more of the fasteners F of the present invention are provided around the rim 5 of the basket for securing the top in position and, in the present instant, four of such fasteners are shown and are preferably equi-spaced around the periphery of the rim of the basket.

- 10 Each of the fasteners F comprise a length of flexible or malleable wire (which can be bent by the fingers of the hand) bent upon itself, at its medial portion, to form a U-shaped loop. The free ends Y of the loop 15 are driven for a distance through the hoops 11 and 12 from the inner side of the basket so that legs 17 thereof will project on the outside of basket. These leg portions 17 are bent upwardly to lie substantially parallel 20 with the side wall of the basket and project above the edge thereof for a distance, preferably, slightly greater than the thickness of the cover, in order that the extremities Y thereof will project above the upper surface 25 of the cover T. The closed end portion 18 of the loop is extended upwardly on the inside of the basket and projects for a distance considerable beyond the upper end of the members 17.
- 30 Thus, it will be seen that the fastening member F consists of a unitary piece of material which is permanently secured to the basket and provides interengageable members 17 and 18 which may be bent to interlocking position, the members being spaced 35 apart so as to receive between them the rim portion 15 of the cover and thereby prevent the radial shifting movement of the cover in either direction off of the top edge of the 40 basket, while another of the fasteners F is being fastened. It is preferred also that the loop or bight member 18 be arranged on the inside of the basket and of such length as to extend through an opening 16a in the cover, 45 whereby it may be bent downwardly around the edge of the rim 15 of the cover and over the legs 17 for interlocking engagement therewith, as clearly shown in Figure 3, although the arrangement of these parts 17 and 18 may 50 be reversed without departing from the spirit of the invention. The leg portions 17 are then bent downwardly through the loop 18 of the fastener and over the bight X thereof in interlocking position therewith, thus securely and firmly holding the cover T in position 55 on the edge of the basket. When in this downwardly extending position, the extremities Y of the member 17 preferably lie below the lower edge of the hoop 12 so that the 60 finger may be readily inserted in back of said member 17, in the clearance there provided, so that said member may be easily moved upwardly in order that the bight or loop X may be moved or disengaged from interengaging 65 relation therewith to the position shown in

Figure 2 so that the cover T may be removed from the basket.

As seen from the drawing, the fastener of the present invention is preferably applied at the time the basket is fabricated with its 70 interengaging parts lying on opposite faces of a sidewall of basket and substantially parallel with the sides thereof so that they will not hinder the nesting or stacking of the baskets for shipping purposes and will not 75 hinder the packing or removing of the contents of the basket and will not injure the contents of the basket; that no separate or independent fasteners are required to be attached to the top or cover T; that in applying the cover T to the basket, its edge is received between the upstanding spaced portions 18 and 17 of the fastener and thereby held from radial shifting movements during the fastening operation thereby insuring that the edge or rim hoop 15 of the cover will always lie upon the top edge of the basket; and, when the parts 17 and 18 have been moved to interlocking position as 85 shown in Figures 3 and 4, each fastener engages the opposite sides of the rim 15 of the cover T and prevents shifting movement of the cover, which movement in other forms of fasteners very frequently loosens or destroys the fasteners, resulting in attendant disadvantages well recognized in the 90 art.

As shown in Figure 5, the leg portions 17 of the fastener may be twisted together or they may be of unequal lengths, as shown 100 in Figure 6, so that only one of the leg portions forms the interengaging member which interlocks with the bight of the fastener.

What is claimed is:

A fastener for a receptacle having a reinforcing hoop at the top of said receptacle, 105 said fastener comprising a substantially U-shaped length of wire having an open and a closed end, said open end being driven through the side of said receptacle and said reinforcing hoop, one of said ends being bent upwardly on the inside of said receptacle and adapted to extend through an opening in the cover therefor and then bent downwardly over the rim of said cover, the 115 other of said ends being bent upwardly on the outside of said receptacle, the open end of said fastener passing through the closed end thereof and the said open end being then bent to positively engage said closed 120 end.

In testimony whereof, I affix my signature.
